UNITED STATES PATENT OFFICE.

MICHAEL B. KATO, OF DUQUESNE, PENNSYLVANIA.

DOUBLE-HEATING COMBINATION BOILER.

Application filed February 16, 1921. Serial No. 445,523.

To all whom it may concern:

Be it known that I, MICHAEL B. KATO, a citizen of the United States, residing at Duquesne, in the county of Allegheny and State of Pennsylvania, have invented a certain new and useful Improvement in Double-Heating Combination Boilers, of which the following is a specification.

My object is to provide a construction and combination which will utilize as far as possible, the heat from the burner for quickly generating water into steam and re-heating said steam in the coils previous to its exit from said coils into a pipe that carries the said steam or hot water to its determined place of usage.

A further object is to provide a combination boiler which with very little alternation is converted into a double heating hot water boiler adapted for domestic use.

A further object is to provide a construction, the members of which are so arranged as to reduce to a minimum the foreign resistance to expansion of said members from the heat.

A further object is to provide a double heating combination boiler, wherein the volume of coils are reduced, thereby reducing the distance of travel of steam or hot water within said double heating combination boiler, thereby reducing the friction travel of steam or hot water within said apparatus to a minimum.

A further object is to provide a second outlet from the boiler into the pipe coils to increase the supply of heated fluid from the boiler into the coils, if so desired.

My invention also consists in certain other novel construction and combination and arrangements of parts, as will be hereinafter more fully described.

In the accompanying drawings, illustrating my invention:—

Figure 1 is a vertical section of one form of my invention;

Fig. 2 is a horizontal section on line 2—2 of Fig. 1;

Fig. 3 is a horizontal section on line 3—3 of Fig. 1; and

Fig. 4 is a vertical section of another form of the invention, partly in elevation.

Like numerals designate like parts in each of the several views.

Referring to the drawings, I provide a jacket 1 having a suitable door 2. Jacket 1 is provided with suitable annular flanges

15 on which a series of pipe coils 13 are suitably mounted in a compact manner so as to form a truncated conoid or circular ridged surface surrounding the upper half 60 of the sphere part of the spheroidal boiler 3, but in spaced relation to said boiler 3, as shown in the drawings.

Portion 12 of the cap coils encircles the cap-coupling 5, which is screwed on the 65 neck 4 of the boiler 3. The intake end of pipe coil 12 opens into a conduit or pipe 11, which is connected by a suitable union 10, with a short pipe 9, which extends through the cap-coupling 5, and opens into 70 the neck 4 of the boiler 3.

I further provide a separate conduit or pipe 6, extending into and through cap-coupling 5, and through the neck of the 75 boiler 3, down half the distance or more into the boiler 3, and having openings 7 at its lower end for the discharge of water into the boiler 3.

I provide a cylindrical cap coupling 5, having in one end three openings or holes 80 extending in towards the opposite end in said cap coupling 5, opening into one large cylindrical opening in said opposite end of said cap coupling 5, as illustrated in the drawings.

Into and through the three holes in cap-coupling 5 are screwed the three pipes or conduits 8, 9 and 6, respectively. Pipe 6 is extended downward through the cap-coupling 5 into the boiler 3, said pipe 6 being a conduit for water which is to be discharged at its lower end opening 7 into boiler 3, said water thereby coming in contact with the inside heated surface of boiler 3.

I provide a sleeve 16, but in spaced relation to the cap-coupling 5 or neck 4 of the boiler 3, said sleeve 16 surrounding the pipe coils 12, as shown.

I also provide a suitable covering 17 of 100 asbestos or other non-heat conducting material on the outside surfaces of the sleeve 16 and coils 13, and extending down on the outside surface of jacket 1, as shown in the drawings, even with or a little lower than 105 the base of the boiler 3.

I provide a suitable conventional burner (not shown).

The several pipes are preferably threaded and screwed into cap-coupling 5, said cap-coupling 5 being screwed on neck 4 of the boiler 3.

In operation, the heat from the burner passes upwards, thereby impinging first against the lower half of the outside surface of the boiler 3. Then said heat passes 5 gradually upwards through the space which is formed between the boiler 3 and the truncated conoid gradually inclined circular rigid surface, which is formed by coils 13, and on up through the space between sleeve 10 16 and cap-coupling 5 or neck 4 of the boiler 3, the coils 13, in conjunction with boiler 3, forming the above-described shaped passageway for the heat to pass through.

The heat is therefore utilized in a most 15 efficient manner for heating water in the boiler 3, and re-heating same in coils 13 and 12, or for converting water into steam in boiler 3, and re-heating same in coils 13 and 20 12.

25 The starting point of flow of hot water or steam towards its determined place of passage, or towards the point of termination, that is at the discharging end of coil 14, begins in boiler 3, travels up through the space surrounding pipe 6 in neck 4, of the boiler 3, then into a conduit or pipe 9, by which means it is directed into pipe 11, said pipes or conduits 9 and 11 being connected by a suitable union 10.

30 By means of pipe 11 it is carried into the receiving end of coils 12, traveling in said coils in a gradual downward gradually outwardly extending circle in coils 13, towards or to the discharging end 14 of the pipe coils 35 13, said end 14 being bent outwardly and protruding out through the side of the jacket 1 an asbestos covering 17.

It will also be noticed that the cap-coupling 5 is adapted to hold the three pipes or 40 conduits, 8, 9 and 6, respectively, rigidly in their positions, as shown.

In Fig. 1 my apparatus, as is shown, is adapted for steam production. Therefore the boiler 3 and coils 12 and 13, in conjunction with one another, act as a steam reservoir, capable of holding a large volume of steam, said steam being converted from a very small amount of water on the order of a flash. Therefore there is no fixed water 50 level. Jacket 1 functions to support the pipe coils 13, and to retain the heat, in conjunction with coils 13 and sleeve 16.

Referring to Fig. 4, there is illustrated a modified form of the invention adapted for 55 the purpose of producing hot water readily in sufficient quantity for domestic use. This form of the boiler has a stem 18 at the bottom, connected by a suitable union 19 with the pipe line 6^a, for the inflow of water 60 through the channel 7^a. In this form of my invention members 6 and 8 are eliminated. Cap-coupling 5 is also altered in construction, as shown in Fig. 4.

The boiler 3 and coils 13 and 12 and all 65 pipes are always full of water to their re-

spective capacity. Water is supplied under pressure through pipe 6^a, channel 7^a, and stem 19 into boiler 3, and into pipe 11 and coils 13, said water being heated in boiler 3, and re-heated in coils 13, thereby keeping 70 in reserve a large supply of hot water for use.

In other respects the construction and the circulation of hot water is substantially the same as heretofore described, save as to 75 minor departures in the shape and disposition of certain parts, as shown.

What I claim is:

1. In an apparatus of the class described, the combination of a boiler, a series of pipe coils, a conduit for the supply of water directly into the boiler, a second conduit for the discharge of steam or hot water from the boiler into a series of pipe coils, the major portion of said coils being in a compact relation to one another, and forming a truncated conoid or cone shaped series of pipe coils gradually expanded downward to form a circular ridged wall around the upper half of said boiler but in a spaced relation to said boiler, a cylindrical cap-coupling 80 to function as a means by which the boiler and conduits are connected onto one another and securely held in position by same, and a jacket supporting the aforesaid 85 pipe coils and functioning in conjunction with the pipe coils to retain the heat used in heating the boiler and coils.

2. In an apparatus of the class described in claim 1, the combination of a bulb or spheroidal shaped boiler, a cylindrical cap-coupling having three channels through one end and opening into a large cylindrical opening towards the opposite end in said cap-coupling, a conduit opening into the 100 boiler to discharge water directly into said boiler, a series of pipe coils encircling the outer surface of the upper half of the sphere part of the boiler, but in spaced relation to said boiler, said series of coils being arranged close together and supported in their determined shape, a sleeve encircling the cap-coupling, or the neck of the boiler but in spaced relation thereto, a jacket supporting 105 the pipe coils by means of a number of small annular flanges, said jacket and flanges being in spaced relation to said boiler, said jacket functioning to retain the heat supply to the boiler, and to direct same through the annular passage between the pipe coils and the outer surface of the boiler, and inside of sleeve above the boiler, and a discharge pipe 110 in which the intake end of the pipe coils terminates.

3. In combination with the apparatus described in claim 2, a non-heat conducting covering mounted on a series of pipe coils and on the outside surface of the jacket, and on the outside surface of the sleeve, about 115 the cap-coupling or the neck of boiler, said 120

125

130

non-heat conducting covering extending from the jacket at or a little below the base of the boiler on up near to the upper end of the sleeve about the cap-coupling or neck of the boiler.

4. In combination with the apparatus described in claim 2, a non-heat conducting covering mounted on a series of pipe coils and on the outside surface of the jacket, and

on the outside surface of the sleeve, about 10 from the cap-coupling or the neck of boiler, said non-heat conducting covering extending from the jacket at or a little below the base of the boiler on up near to the upper end of the sleeve about the cap-coupling or neck 15 of the boiler.

MICHAEL B. KATO.
